(57) **CLAIM**

The ornamental design for a pouch for personal belongings, as shown and described.

DESCRIPTION

The file of this patent contains at least one photograph executed in color. Copies of this patent with color photographs will be provided by the Office upon request and payment of the necessary fee.

1. Pouch for personal belongings

1.1 : Perspective

1.2 : Front

1.3 : Back

1.4 : Top

1.5 : Bottom

1.6 : Right

1.7 : Left

1.8 : Perspective

1.9 : Perspective view of the open state

This product is a pouch that makes it easy to see the stored items by using a transparent material, and it is easy to take out the stored items by opening it wide like the perspective view of the open state; the main body except for the zipper is transparent, and the bottom plate is translucent; fig. 1.1 is
